UNITED STATES PATENT OFFICE.

WILLIAM HENRY DILLON, OF GLASGOW, KENTUCKY.

SHOE-FASTENING.

SPECIFICATION forming part of Letters Patent No. 338,044, dated March 16, 1886.

Application filed October 17, 1885. Serial No. 180,200. (No model.)

To all whom it may concern:

Be it known that I, WILLIAM HENRY DILLON, a citizen of the United States, and a resident of Glasgow, in the county of Barren and State of Kentucky, have invented certain new and useful Improvements in Shoe-Fastenings; and I do hereby declare that the following is a full, clear, and exact description of the invention, which will enable others skilled in the art to which it appertains to make and use the same, reference being had to the accompanying drawings, which form a part of this specification, and in which—

Figures 1 and 2 are perspective views of as much of a shoe as is necessary to show my invention, Fig. 1 illustrating the invention applied to a shoe designed as a button-shoe, and Fig. 2 showing it applied to a lace-shoe. Fig. 3 is a view of the inner portion of one of the fasteners, and Figs. 4, 4^a, 5, and 5^a are sectional views of the different forms of the eyelet-fastenings.

Similar letters of reference indicate corresponding parts in all the figures.

My invention has relation to lace-eyes for shoes; and it consists in the improved construction and combination of parts of a lace-eye and its fastening, as hereinafter more fully described and claimed.

In the accompanying drawings, the letter A indicates the portion of the shoe upon which the buttons in a button-shoe are secured, and B is the flap, which in such a shoe is provided with the button-holes. The lace-eyes C are secured upon the outer side of the portion A at a distance from the edge, and upon the inner side of portion B, near the edge, so that they will register or be on a line with those upon A, and consist of a round eye, D, having flat shanks E E, which are formed with oblong perforations F. The rivet G passes through the leather of the shoe and through these perforations, and is riveted over the edges of the perforation in the exposed shank, the opposite or inner ends of the rivets upon the portion A being flat and smooth, and the outer ends of the rivets upon the portion B being round, as shown at H, to imitate a shoe-button. A lace-cord, J, is passed through the lace-eyes, being secured at the lower end of

the free edges of the parts of the shoe, and may be secured at its upper end in any suitable form of a lace holding or clamping device.

When the lace-cord is drawn tight and secured at its upper end, the edges of the portions A and B of the shoe are drawn together, so that the greater part of the eyelets and their fastenings are covered, and the shoe will have the appearance of a button-shoe, while it will have the advantage of being easily opened by simply releasing the cord, when the shoe may be removed from the foot, or in closing the parts together by drawing the cord and securing its end.

In Fig. 2 the eyes are shown secured upon the inner sides of the portions of the shoe at each side of the slit, and thereupon passed out through apertures L in the said portions, and the rivets are shown considerably smaller, so as to be less conspicuous than the buttons shown in Fig. 1, it being desirable in this form of a lace-eye to show as little of the eye and its fastening as possible. Two lace-cords are preferably used in this form of lacing, and the cords are operated in the usual manner, drawing them upward, and consequently drawing the portions together.

In Fig. 5^a the shanks of the eye are shown clamping both sides of the leather at the edge of the same, the rivet passing through the perforated shanks and holding them together, and this fastening is more desirable where it is not desired to draw the edges of the two portions very close together, while when it is desired to draw the edges of the portions close together, so as to cause one to overlap the other, the form shown in Fig. 2 is the most desirable, the same form being shown in section in Fig. 5.

In Fig. 4 is shown in section the form used in the shoe made in imitation of a button-shoe, and in Fig. 4^a is shown a form in which the button part of the fastening is separate from the rivet. It will be noticed that I use a fastening having an oblong aperture and a rivet having an oblong shank.

The inner sides of the outer ends of the lace-eyes are rounded, so as to prevent cutting or any undue wear of the eyes upon the cords.

Having thus described my invention, I claim and desire to secure by Letters Patent of the United States—

The combination, with the flaps of a shoe, 5 of two series of lace-eyes riveted thereto, said rivets having oblong shanks, and the shanks of the lace-eyes having oblong apertures, as shown and described.

In testimony that I claim the foregoing as my own I have hereunto affixed my signature in presence of two witnesses.

WILLIAM HENRY DILLON.
